UNITED STATES PATENT OFFICE.

JOHN MAYOTTE, OF ODANAH, WISCONSIN, ASSIGNOR OF ONE-HALF TO JOSEPH SOULIER, OF ODANAH, WISCONSIN.

METALLIC BEAM SPLICE.

Application filed February 9, 1923. Serial No. 617,961.

To all whom it may concern:

Be it known that I, JOHN MAYOTTE, a citizen of the United States, and resident of Odanah, in the county of Ashland and State of Wisconsin, have invented certain new and useful Improvements in Metallic Beam Splices; and I do hereby declare that the following is a full, clear, and exact description thereof.

This invention relates to metallic beam splices, and is particularly directed to a splice applicable to building beam or building structure joints, to rail connections for tracks and for similar purposes.

Objects of this invention are to provide a metallic beam splice which has a double lock joint which will continue to hold the beam or rails from relative turning motion, although the bolts and fish-plates may have become detached.

Further objects are to provide a metallic beam splice which is so constructed that one beam end may not be lifted directly upwardly from the other, although the attaching bolts may have become removed, which will prevent spreading of rails, and which is stiff, self supporting and strong.

Although the invention is applicable to several different uses, it has been illustrated in the accompanying drawings as applied to a rail joint, and in such drawings—

Figure 1 is a side elevation of the joint.

Figure 2 is a plan view of the structure shown in Figure 1.

Figure 3 is a section on the line 3—3 of Figure 2.

Figure 4 is a plan view of one of the rail ends.

Figure 5 is a plan view of the cooperating rail end.

Referring more particularly to the drawings, it will be seen that a pair of rail ends have been illustrated, such rails comprising a web 1, a base or flange 2, and a head 3. For convenience of description, the corresponding portions of the right hand rail in Figure 1, have been indicated 1', 2' and 3', respectively. These rails are arranged with their ends juxtaposed, and are cut away, as indicated in Figures 4 and 5. One of the rails, for instance the left hand, has its web 1 cut out, and the one side of the head 3 cut away, thereby leaving a projecting tongue 4. The flange 2, is similarly

cut away, thereby leaving a projecting tongue 5. It is to be noted from reference to Figures 3 and 4, that the tongues 4 and 5 are arranged upon opposite sides of the center line. The corresponding end of the cooperating rail has its web 1' left intact. However, a portion of the head is cut away up to the web 1', thereby leaving a projecting portion 6 integrally joined to the web and extending only to one side thereof. The flange is similarly cut away on the opposite side of the web, thereby leaving a projecting portion 7 integrally joined to the web and extending therefrom in an opposite direction of the portion 6, as may be clearly seen by reference to Figures 3 and 5.

In assembling the rails, the end shown in Figure 5 may be slid directly longitudinally and into the space provided by the cut away portions in the other rail, or such rail shown in Figure 5 may be slightly tilted and slid sideways through the cut-out portion provided between the tongues 4 and 5 in the rail illustrated in Figure 4. When the rails are in this position, it will be noted that the portions 4 and 6 complete the head of the rail and the portions 5 and 7 complete the flange.

A pair of fish-plates 8 and 9, are positioned upon opposite sides of the web and are suitably apertured to receive bolts 10 passed through such apertures and through the aligning apertures in the webs 1 and 1', as illustrated in Figures 1, 2 and 3, suitable clamping nuts 11, being provided upon the threaded ends of the bolts in the usual manner. These fish-plates further strengthen the joint and bridge the gap between adjacent portions of the rail.

It is to be particularly noted that the turning of one rail portion with reference to the other rail is prevented by the projecting interlocking tongues, and that neither rail may bounce or otherwise move upwardly from the adjacent end, even though the attaching bolts may have become shaken out.

It will be seen, therefore, that spreading of the rails, or dangerous turning, or lack of alignment is prevented by this construction, and that the stresses tending to cause relative motion between the rail ends are borne jointly by the fish-plates and by the interlocking portions of the rails.

Although the invention has been described and illustrated as applied to the rails of railroad tracks, it is obvious that it may be applied to I-beam constructions or to other building beams, and that it will provide a double lock and contribute to the rigidity, strength and safety of the joint. It is, therefore, to be understood that although one form of the invention has been described in considerable detail, the invention may take other forms and is to be limited only as defined in the appended claims.

It is further to be understood that the term "beam", as used in these claims, is to be understood as covering the usual beam construction, railway rails, and other similar articles.

I claim:

1. In a beam splice, the combination of a pair of juxtaposed beam ends having interlocking tongues positioned upon opposite sides of a central web, a pair of fish-plates bolted through such web, one of said ends having the web wholly cut away adjacent such end and the other end having a

web adapted to fit within the cut away portion.

2. In a metallic beam splice, the combination of a pair of juxtaposed beam ends each having a head, a web, and a lower flange, each of said ends having a tongue forming a continuation of said head and flange respectively, and said head and flange being cut out adjacent said tongues to receive the corresponding tongues of the other beam end, one of said rail ends having the web cut away adjacent the tongue, and the other of said ends having the web in position adjacent its tongue and integrally joined thereto, whereby said ends may be interlocked to form a substantially continuous head and flange adjacent said tongues, and a pair of fish plates bolted through the webs of the adjacent rail ends.

In testimony that I claim the foregoing I have hereunto set my hand at Odanah, in the county of Ashland and State of Wisconsin.

JOHN MAYOTTE.
